Attorney

UNITED STATES PATENT OFFICE.

ERICA KRUG, OF GARDNER, ILLINOIS.

ELECTRIC CLOTHESBRUSH.

Application filed December 30, 1925. Serial No. 78,378.

This invention relates to electric clothes brushes and has for its primary object to provide such a brush that simulates the construction of the well known vacuum cleaner in order that clothes may be properly cleaned, and this in a quick manner. The invention comprising a rotary brush, and suction means simultaneously operable by a small electric motor that is so interconnected as to provide a small, light and portable device.

Other objects will become apparent as the nature of the invention is better understood, the same comprises the novel form, combination, and arrangement of parts herein-after more fully described and shown in the accompanying drawing, and claimed.

In the drawing wherein like reference characters indicate corresponding parts throughout the several views.

Figure 1 is a side elevation of my improved electrically operated brush.

Figure 2 is an enlarged detail section through the forward end thereof, and

Figure 3 is a fragmentary vertical section through the extreme forward end thereof for more clearly disclosing the brush construction and its mounting means.

Now having particular reference to the drawing, my novel brush constitutes the provision of a small and light electric motor 5, the casing of which is formed at its forward end with a longitudinally extending tube 6 for providing a handle for the brush. The forward end of this tube is provided with a fan housing 7, the front wall 8 of which, Figure 2, is provided with an opening 9, and the side wall of which is provided with a discharge nozzle 10 open to the atmosphere or for communication with a dust bag or the like through use of conventional means.

Secured to the front side of the fan casing 7 is a brush carrying casing 11, the end of the nose portion of which is open, Figures 1 and 3, and through which projects the bristles of a pair of spaced brushes 12-12 mounted upon a shaft 13 that is journaled within openings at the end walls of said casing nose.

The armature shaft 14 of the electric motor extends through the tube 6, casing 7 and casing 11, a bearing 15 being provided at the

front end of the tube while a bearing 16 is provided for the forward end of the shaft, 55 the same being secured to the removable face plate 17 which covers the open front face of the brush casing.

Secured to the armature shaft 14 within the fan housing 7 is a suction fan 18 while secured to the shaft 14 adjacent its forward end is a pulley 19 over a pulley 20 upon the brush carrying shaft 13 and intermediate said brushes, Figure 3. A suitable belt 21 is trained over these pulleys whereby a rotation of the armature shaft 14 will impart a rotation to said brush shaft.

It will be obvious that in the operation of the device suction is created by the fan 18 for drawing air upwardly through the opening in the nose of the brush casing 11 for extracting dust, dirt, and the like from the clothes, which is stirred up and removed from interstices of the clothes by the action of the brushes 12-12 rotating thereagainst. 75

Incident to the use of the brush, it will be appreciated that the tube or tubular portion 6 in conjunction with the contiguous portions of the motor and fan casings will constitute a comfortable handle for the efficient 80 wielding of the brush and such a handle that casual endwise movement of the device in the hand of the operator is precluded, and the operator is enabled to exert considerable stress in either direction endwise on the 85 brush for the forcible movement of the brush at right angles to the handle against clothes or cloth.

The advantages of a clothes brush of this character will be readily appreciated by 90 those skilled in the art. Even though I have herein shown and described the preferred embodiment of the invention with which I am at this time familiar, it is nevertheless 95 to be understood that minor changes may be made without departing from the spirit and scope of the appended claim.

Having thus described the invention, what I claim as new is:—

A clothes brush consisting essentially of a 100 motor casing, a motor therein, a fan casing spaced in front of the motor casing, a rotary fan in the fan casing, a brush casing in front of and communicating with the fan casing and extending forwardly and downwardly 105 from the fan casing and gradually increased

2
in width as it recedes from the fan casing and having a lower portion spaced below the plane of the fan casing and an opening in said lower portion, a transverse rotary brush in the brush casing and protruding through said opening, a tubular portion of reduced cross section at right angles to said brush and joining the motor and fan casings; said tubular portion and the contigu-

ous portions of the motor and fan casings 10 shaped to form a handle, a shaft operable by the motor and extending through said tubular portion and the fan and brush casings and carrying the fan, and a driving connection in the brush casing and between 15 said shaft and brush.

In testimony whereof I affix my signature.
RICA KRUG.
